COMBINED CONDIMENTS DISPENSER SET AND TOOTHPICK HOLDER

Thomas H. Davis, Brooklyn, N. Y., assignor to
Davis Products Corp., Brooklyn, N. Y., a corpora-
tion of New York

Application October 19, 1953, Serial No. 27,214

Term of patent 14 years

(Cl. D44—22)

To all whom it may concern:

Be it known that I, Thomas H. Davis, a citizen of the United States of America and resident of Brooklyn, county of Kings, city and State of New York, have invented a new, original and ornamental Design for a Combined Condiment Dispenser Set and Toothpick Holder, of which the following is a specification, reference being had to the accompanying drawing, forming a part thereof, and which is a perspective view of a combined condiment dispenser set and toothpick holder embodying my new design.

A characteristic feature of the design resides in the toothpick holder element in its relation to and its association with the other portions shown.

I claim:

The ornamental design for a combined condiment dispenser set and toothpick holder, as shown and described.
